SELECTIVE REMOVAL OF TERTIARY OLEFINES

Richard M. Deanealy, Berkeley, Calif., assignor to
Shell Development Company, San Francisco,
Calif., a corporation of Delaware

No Drawing. Application July 17, 1933,
Serial No. 680,781

19 Claims. (Cl. 260—166)

According to the present invention, advantage is taken of the different rates of reaction of secondary and tertiary olefines and saturated bodies with free halogen, particularly chlorine, to render tertiary olefines innocuous in their admixtures with secondary olefines, in the presence or absence of paraffin hydrocarbons. Not only is the rate of halogenation maintained under control but also the halogen forms predominantly a substitution product with tertiary olefines.

The source of the stock material is immaterial. Mixtures of paraffin and olefine hydrocarbons, including tertiary olefines, can be obtained by the pyrolytic treatment or cracking of mineral oils as petroleum, petroleum products, coal tar, pitches, coal, peat, shale oil, and like or related carbonaceous material.

If desired, the cracked stock material can be employed as mixtures of olefine and paraffin hydrocarbons containing varying numbers of carbon atoms per molecule or may be fractionated into suitable fractions which predominate in hydrocarbons containing the same number of carbon atoms to the molecule as a butane-butene fraction, a pentane-amyrene fraction, a hexane-hexene fraction and the like or may comprise a plurality of fractions such as a fraction consisting predominantly of hydrocarbons containing 4 and 5 or 5 and 6 or 4, 5 and 6 carbon atoms to the molecule.

A typical fraction would comprise the normal paraffin hydrocarbon, the iso saturated aliphatic hydrocarbon, the secondary olefines, the tertiary olefine and, perhaps, small amounts of diolefines.

In carrying out my invention, it is desirable that moisture be absent, i. e. it is preferable to operate with substantially anhydrous reactants since it appears that the presence of water vapor catalyses to some extent the addition reaction of hydrochloric acid to tertiary olefines. Operating with dry reactants also avoids or minimizes corrosion losses.

For example, working with a hydrocarbon mixture containing isobutylene, the following reactions are possible when resorting to halogens such as chlorine:

60 The presence of moisture favors reaction 3, par-

ticularly at elevated temperatures and/or super-atmospheric pressures.

Around 90% of the theoretical yield of tertiary olefine monochloride is obtainable based on the chlorine input.

It is preferable, if the object is to make tertiary halo olefines in good yields, to add the halogen in amount considerably less than equivalent to the tertiary olefine content and accept a lower yield on the olefine base, but higher on the halogen bases.

The process can be conducted in the gaseous, liquid or mixed gaseous-liquid phase, i. e. a rain of hydrocarbons can descend countercurrent to ascending chlorine gas in a tower which may or may not be packed in the conventional manner or possess plates. The hydrocarbon mixture, if in the gaseous phase, can be conducted through a series of towers, where it comes into contact with static or flowing (preferably countercurrent) liquid containing chlorine. If desired, the concentration of the chlorine in the chlorine liquid may vary with the different stages of treatment, the initial stock material first being treated with weak chlorine fluid and then with progressively stronger concentrations of chlorine. Inert diluents may be incorporated with the halogen and/or reactants and oxygen may be utilized as inhibitor of the substitution reaction of saturated organic compounds as paraffin hydrocarbons and their derivatives with halogen.

My copending applications, Serial No. 574,462 filed November 11, 1931 and Serial No. 631,758 filed September 6, 1932, disclose still other specific methods of executing a halogenation process.

The process can be conducted in batch, intermittent or continuous fashion.

The unsaturated monochlorides can be recovered from the unattacked materials in various ways. If the stock material is a normally gaseous mixture, the resulting monochlorides are liquids and hence, separate out easily. If the stock material is a normally liquid mixture, the resulting monochlorides can be recovered therefrom by extraction with suitable solvents, by distillation and the like.

Not only the mono-tertiary olefines but their homologues, the dimers, trimers, etc., as diisobutylene, ditertiary amyrene and the like can be halogenated similarly. For example, diisobutylene yields monochlor diisobutylene upon chlorination which is not so readily attacked by chlorine as long as the more reactive diisobutylene is present to preferentially combine with the chlorine.

The preferential reaction may be carried out with tertiary olefines in a mixture with one or more components as secondary olefines, paraffins, chlor paraffins, tertiary chlor olefines, i. e. unsaturated monochlorides resulting from the

chlorination of the original tertiary olefines, saturated halogenated hydrocarbons, unsaturated halogenated hydrocarbons and the like.

The following examples are cited for exemplary purposes only and are not to be regarded in any way as limitative.

Example I

7040 gms. of a cracked hydrocarbon fraction containing 37.2% isobutylene, 33.0% secondary butylenes and 29.8% butane were contacted with 1490 gms. of chlorine and permitted to react. Upon analysis of the crude chlorides recovered, it was found about 75% of the total chlorine reacted with isobutylene; about 5 to 10% of the total chlorine reacted with the secondary butylenes and about 1 to 3% of the total chlorine reacted with butane. The remainder of the chlorine was unaccounted for or lost in the exit gas.

This example demonstrates that it is easy and economically advantageous to make unsaturated tertiary monohalides without first concentrating tertiary olefines in their admixtures with other hydrocarbons, chlor-derivatives, and the like.

A technical pentane-amylenes cut made by straight fractionation from cracked products and having the composition:

Example II

	Per cent by weight
Tertiary amylenes.....	23.8
Secondary amylenes.....	33.3
Pentanes	42.9

yielded the following results. Analysis of the chlorinated products showed that chlorine had reacted with 70% of the tertiary amylenes, 8% only of the secondary amylenes and substantially with none of the pentane.

Once the tertiary olefines have been removed from their admixtures, the unattacked portion is available for other reactions. The secondary olefines present can then be halogenated with a halogenizing agent as chlorine, hydrochloric acid; or reacted with acids as phosphoric acid, sulfuric acid, the carboxylic acids, the benzene sulfonic acids and homologues, the corresponding acid anhydrides, acid salts of polybasic mineral acids as the alkali-metal acid salts of sulfuric acid, phosphoric acid and the like, the alkyl acid esters of polybasic acids such as the methyl, ethyl, propyl, butyl, isobutyl, amyl, isoamyl and higher alkyl acid esters of sulfuric and phosphoric acids; or combined with phenolic bodies to yield corresponding alkylated compounds, or directly hydrated to yield alcohols; or combined with alcohols to yield ethers, etc.

The preliminary halogenating treatment is customarily carried out at low temperatures (0-60° C.) preferably in the dark. The exact operating technique is dependent on the primary objective of the operator: whether it is desired to obtain an olefine monohalide or to selectively remove tertiary olefines from hydrocarbon mixtures and the like.

The chlorinated mixture of tertiary olefines serves a useful function in the chemical industry and may be used per se or as an intermediate for further chemicals.

While I have in the foregoing described in some detail the preferred embodiment of my invention and some variants thereof, it will be understood that this is only for the purpose of making the invention more clear and that the invention is not to be regarded as limited to the

details of operation described, nor is it dependent upon the soundness or accuracy of the theories which I have advanced as to the advantageous results attained. On the other hand, the invention is to be regarded as limited only by the terms of the claims, in which it is my intention to claim all novelty inherent therein as broadly as is possible in view of the prior art.

I claim as my invention:

1. A process for the selective halogenation of tertiary olefines in their admixtures with compounds of the class consisting of, secondary olefines, saturated halogenated hydrocarbons and unsaturated halogenated hydrocarbons which comprises, reacting a mixture thereof with only sufficient free halogen to effect the substantially selective halogenation of the major part of the tertiary olefine present.

2. A process for the selective halogenation of tertiary olefines in their admixtures with compounds of the class consisting of, secondary olefines, saturated chlorinated hydrocarbons and unsaturated chlorinated hydrocarbons which comprises, reacting a mixture thereof with only sufficient free chlorine to effect the substantial selective chlorination of the tertiary olefine present and subsequently separating the chlorinated tertiary olefine from the unchlorinated products.

3. A process for the substantial transformation of tertiary olefines to the corresponding unsaturated halides in the presence of secondary olefines without substantial halogenation of the latter which comprises, reacting a mixture of secondary and tertiary olefines with substantially not more than the stoichiometric amount of free halogen corresponding to the tertiary olefine content.

4. A process for the substantial transformation of tertiary olefines to the corresponding unsaturated chlorides in the presence of secondary olefines without substantial chlorination of the latter which comprises, reacting a mixture of secondary and tertiary olefines with substantially not more than the stoichiometric amount of free chlorine corresponding to the tertiary olefine content.

5. A process for the selective halogenation of tertiary olefines in the presence of secondary olefines and paraffin hydrocarbons without substantial halogenation of the latter which comprises, reacting a mixture of paraffin hydrocarbons and secondary and tertiary olefines with only sufficient free halogen to effect the substantially selective halogenation of the major part of the tertiary olefine present.

6. A process for the selective halogenation of tertiary olefines in the presence of secondary olefines and paraffin hydrocarbons without substantial halogenation of the latter which comprises, reacting a mixture of paraffin hydrocarbons and secondary and tertiary olefines with only sufficient free halogen to effect the substantially selective halogenation of the tertiary olefine present and in the presence of free oxygen.

7. A process for the selective halogenation of tertiary olefines in the presence of secondary olefines and paraffin hydrocarbons which comprises, reacting a mixture of paraffin hydrocarbons and secondary and tertiary olefines with only sufficient free halogen to effect the substantially selective halogenation of the tertiary olefine present, separating the halogenated tertiary olefine from the unattacked products and subjecting the latter to reaction with a compound capable of combining with a secondary olefine.

8. A process for the selective halogenation of chlorine to effect the substantially selective chlorination of the tertiary amylene present.
- 5   tertiary olefines in the presence of secondary olefines and paraffin hydrocarbons which comprises, reacting a mixture of paraffin hydrocarbons and tertiary olefines obtained by a reaction between a mixture of tertiary olefines and a free halogen.   5
- 10   bonds and secondary and tertiary olefines with only sufficient free halogen to effect the substantially selective halogenation of the major part of the tertiary olefine present, separating the halogenated tertiary olefine from the un-   10
- 15   attacked products and subjecting the latter to reaction with an acidic compound of the class consisting of acids, acid anhydrides, acid salts and acid esters.   15
9. A process for the selective chlorination of tertiary olefines in the presence of secondary olefines and paraffin hydrocarbons which comprises, reacting a mixture of paraffin hydrocarbons and secondary and tertiary olefines with only sufficient free chlorine to effect the substantially selective chlorination of the tertiary olefine present, separating out the portion acted upon and then treating the unchanged remaining portion with a reagent capable of combining with a   20
- 20   secondary olefine.   20
- 25   10. A process for the selective chlorination of a hydrocarbon fraction consisting predominantly of paraffin hydrocarbons and secondary and tertiary olefines of the same number of carbon atoms to the molecule which comprises reacting said fraction with only sufficient free chlorine to effect the substantially selective chlorination of the tertiary olefine present.   25
11. A process for the selective chlorination of a butane-butene reaction which contains butane and isomeric butenes which comprises, reacting said fraction with only sufficient free chlorine to effect the substantially selective chlorination of the isobutylene present.   30
- 35   12. A process for the selective chlorination of a pentane-amylene fraction which contains pentane and isomeric amylenes which comprises, reacting said fraction with only sufficient free   35
- 40   olefines, which comprises reacting a mixture of secondary and tertiary olefines with only sufficient free halogen to effect the substantial selective halogenation of the tertiary olefine present in excess in the liquid phase.   40
16. A process for the selective halogenation of tertiary olefines in the presence of secondary olefines, which comprises reacting a mixture of secondary and tertiary olefines with only sufficient free halogen to effect the substantial selective halogenation of the tertiary olefine present while maintaining an excess of tertiary olefine.   20
17. A process for the selective halogenation of tertiary olefines in the presence of secondary olefines, which comprises reacting a mixture of secondary and tertiary olefines with only sufficient free halogen to effect the substantial selective halogenation of the tertiary olefine present in excess in the liquid phase.   25
18. A process for the selective halogenation of tertiary olefines in the presence of secondary olefines, which comprises reacting a mixture of secondary and tertiary olefines with only sufficient free halogen to effect the substantial selective halogenation of the tertiary olefine present while maintaining an excess of tertiary olefine in the liquid phase.   30
19. A process for the formation of a monohalogeno olefine from a tertiary olefine, which comprises reacting an excess of the tertiary olefine with free halogen in the presence of tertiary olefine in the liquid phase and removing the products of halogenation substantially as fast as formed.   40
